ABSTRACT

A beverage container filling head including a valve means is provided for controlling flow of fluid through the filling head and an electrically conductive probe extends longitudinally of the filling head. The probe is adapted to be moved an adjustable distance as a separate member from a retracted position within the filling head to an extended position where it projects from the filling head to contact liquid in an associated bottle and control termination of the bottle filling action.

BEVERAGE CONTAINER FILLING HEAD

The present invention relates to filling heads, and especially to filling heads used in automatically functioning machinery adapted to fill a plurality of containers, usually bottles, with materials, usually beverages, in a rapid, efficient and uniform manner.

This invention relates to and comprises an improvement upon the construction disclosed in U.S. Pat. Application Ser. No. 500,863, filed Oct. 28, 1965 by Bruce G. Copping and Kenneth F. Friendship now Patent No. 3,443,608, wherein an apparatus for filling containers with beverages is disclosed. In general, many efforts have been made heretofore to improve upon the functioning of container filling apparatus, and particularly for filling bottles rapidly with beverages. It is very important that the filling heads be rapidly movable to and from engagement with containers or bottles for filling the same, as usually the bottles remain on a rotatable turntable and the filling heads are individually brought down to engage the bottles, and are later individually released. Inasmuch as some of these filling machines operate through, for example, 15 complete filling cycles per minute, it is seen that it becomes a difficult problem just to move the filling heads to and from engagement with the bottles in the required rapid manner. At the same time, efforts are continually being made to speed up the operation of these machines so that if any simplification of the apparatus can be made, or if the motion of the filling heads be improved or simplified to be more easily controlled, such a development would be an appreciable step forward and aid in providing an effective, more rapid filling cycle.

The general object of the present invention is to provide a novel and improved filling head which is characterized by the presence of an axially positioned probe in the filling head movable a selected distance independently of any movement of the other elements therein.

Another object of the invention is to reduce the extent of movement required in a bottle or article filling head to change it from operative bottle engaging position to an inoperative bottle release or discharge position.

Other objects of the invention are to insure that the apparatus of the invention will only function when a satisfactory counterpressure condition has been established in the container to be filled; to provide electrical controls for terminating filling action when a probe provided in the filling head is contacted by the beverage indicating a predetermined filled height in the container; to provide a common fluid power supply for actuating both a beverage input control valve and a probe extension piston or means in the filling head; to position a probe so that it can be moved vertically independently of any movement of the frame of the filling head; to provide a lightweight unit for controlling the probe position and to move the entire relatively heavy filling head assembly only a short distance vertically in the apparatus but to permit an independent and greater length of vertical movement in the probe whereby the probe can be moved axially of the filling head to a retracted position and to an extended position for operative engagement with a bottle and the contents thereof; to provide an improved filling head having desirable operating characteristics; and to provide a lightweight, novel filling head unit which will function rapidly and efficiently with a minimum of maintenance thereon.

In general, the present invention, as one embodiment thereof, relates to a filling head used in apparatus for filling articles with beverage and comprising a frame having a bottom portion for engaging the top of an article, which frame has a tubular section therein in which a valve seat means is provided and a tubular valve means having a bore slidably positioned in the tubular section for flow of beverage through the valve seat means when the valve means is moved to an open position. Beverage is supplied to the tubular valve means under suitable pressure conditions and the valve means is controlled to move to and from valve open or closed positions. A probe is slidably positioned in the bore of the valve means and other means engage the probe to control the position thereof whereby the probe can be moved vertically a desired, independently controlled distance in the filling head.

Reference now is made particularly to the accompanying drawings, wherein:

20 FIG. 1 is a vertical section of a filling head embodying the principles of the invention showing it in operative bottle engaging position prior to the discharge of beverage therefrom;

25 FIG. 2 is a fragmentary vertical section of a portion of the filling head of FIG. 1 and indicating the probe in its extended, operative position; and

FIG. 3 is a fragmentary horizontal section taken on line 3—3 of FIG. 2.

30 When referring to corresponding members shown in the drawings and referred to in the specification, corresponding numerals are used to facilitate comparison therebetween.

With particular reference to the details of the structures shown in the drawings, a filling head is indicated 35 as a whole by the numeral 10, and such filling head may be considered to have as portions thereof a positioning means 20 and a control means 30. The particular invention relates to details of certain portions of the filling head 10, and it should be noted that the positioning means 20 includes a suitable frame 22 that has a tubular, vertically extending section 24 therein in which the components forming certain novel elements in the filling head 10 are assembled and/or secured.

40 In the actual container filling machine with which the filling head 10 would be used, a plurality of individual filling heads normally would be suitably attached to a frame, usually, at the circumference thereof in circumferentially uniformly spaced relationship. Each of these filling heads 10 would have associated therewith one of the positioning means 20 and this positioning means 20 has the vertical position of its frame 22 controlled by suitable means such as an arcuate cam 26 that extends around a portion of the circumference of the machine with which the filling head is associated. Hence, through a part of the rotary movement of the frame or machine on which the filling heads are positioned, the cam 26 is adapted to engage a cam roller 28 suitably attached to and carried by a lower portion of the frame 22, which cam 26 also engages a second cam roller 29 that is suitably secured to and extends from a member of frame 21 of the machine and forming a part of the individual positioning means 20. In all events, the engagement of the cam 26 with the rollers 28 and 29 causes the movable frame 22 to be raised vertically a short distance and this in turn moves the lower end of the filling head 10 out of engagement with the upper end of the neck or top of a bottle B indicated in the

drawings after the bottle has been filled in the cycle of operation of the machine. This movable frame 22 includes a cylindrical section 25 which has a closed lower end and which, in effect, provides a closed end cylinder in which a cylindrical projection or member 27 is telescopically received so as to provide an air spring action between the cylindrical member 27 and the adjacent lower closed end of the cylindrical section 25. A port 127 connects the cylinder 27 to the interior of the section 25 whereby the entrapped air or other gas provided in the chamber formed therebetween will normally tend to move the movable frame 22 and the members carried thereby downwardly to the position of FIG. 1. However, vertical upward movement of the assembly can be provided by compression of the entrapped gas as by the cam 26 engaging the associated cam rollers whereby a limited vertical movement upwardly for the filling head 10 and parts carried thereby is provided when the cam raises the movable frame 22 and cylindrical section 25.

With reference to the controls 30, the fixed frame 21 carries at the upper end thereof a control switch 31 that connects to suitable control means 100 by leads 103 and 104 for control functions, depending upon whether the switch 31 is in its closed or operative position. The positioning of the switch 31 is regulated by means of a piston rod 33 that extends from the switch 31 and is movably associated therewith and with the piston rod 33 engaging a suitable diaphragm 34 associated with the switch. A counterpressure from a bottle or other article to be filled as hereinafter described is transmitted to the lower surface of the diaphragm 34 by gas introduced into the fixed frame 21 and a chamber formed therein adjacent the piston 33 by a supply line or conduit 36, as hereinafter described, that extends from the fixed frame 21 to the bottle being processed, and is in operative communication with the bore thereof. Pressure is provided to the fixed frame 21 below the diaphragm 34 through a bore 35 that connects to a tube 37 that extends to a source of counterpressure gas. Pressure fluid for the lower face of the diaphragm 34 flows through a bore in the fixed frame 21 from a valve 38 which is shown in a closed position and which connects to the bore 35. A control cam roller 39 is slidably positioned in the fixed frame 21 and is moved to the right to the position shown in the drawings by a member 140 operatively engaging the cam roller 39 at one portion of the rotation of the apparatus with which the filling head 10 is associated. Such movement of the cam 39 moves the valve 38 to its closed position but when the member 140 releases the cam, a spring 141 moves the valve 38 to the left to an open position. The valve 38 is opened when the filling head 10 is moved to bottle engaging position. At such time, pressure gas flows through the valve 38, past the diaphragm 34, and to and through the conduit 36 for flow to an engaged bottle to fill it with counter-pressure gas as later described herein.

The actual beverage flow control means in the filling head of the invention are positioned in the tubular section 24 provided in the movable frame 22. A lower end sleeve 40 is attached to the lower end of the tubular section 24 by a lock nut 41 that engages a shoulder 42 provided on this sleeve 40 and which lock nut 41 is threadably engaged with the movable frame 22. A pressure reducing center block 43 is also positioned within the tubular section 24 and an upper end block 44 is re-

ceived in the upper end of the tubular section 24 and extends upwardly therefrom, being retained against axially outward movement by a shoulder or flange 45, on the lower end of the upper end block 44 engaging a counterbored shoulder 46 formed in the tubular section 24 spaced from the upper end thereof.

A resilient ring 47 is suitably attached to and carried by the lower end of the lower end sleeve 40 for sealing engagement with the bottle B when the filling head 10 is moved downwardly a short distance, or otherwise brought into engagement with such bottle B. Any suitable valve means in this instance including a tubular valve seat 48 is provided in the counterbored upper end 49 of the sleeve 40. Flow of beverage through the filling head 10 is controlled by a tubular valve means 50 which is slidably positioned within the filling head 10. The drawings clearly show that an enlarged tubular lower end section 51 is provided in this valve means 50 and such end carries a pair of sealing members, such as O-rings 52 and 53, adjacent the upper and lower portions thereof and which have sealing engagement with the bores of the center block 43 and the lower end sleeve 40, respectively, as shown. However, a plastic-to-metal seal is formed at the lower end of the center block 43 by complementary shapes including an inclined shoulder 150 on the valve means 50. The enlarged end 51 also has a plurality of substantially tangentially directed bores or apertures 54 formed therein for beverage flow therethrough as hereinafter described. Beverage or other liquid being processed is supplied to the filling head 10 through a conventional supply line or tube 60 that connects to a conventional source of beverage under relatively high pressure, such as, for example, about 75 psi. The beverage flows through the tube 60 and a connecting bore formed in the movable frame 22 into an annular distributing chamber or member 61. The pressure reducing center block 43 has a multiple helical thread 62 formed on its periphery and these multiple threads have the upper ends thereof connecting to the distributor chamber 61 at circumferentially spaced portions thereof whereby beverage will flow into the various threads 62 into the spaces defined by the threads in relationship to a spacer sleeve 63 positioned around this threaded portion of the center block 43. The beverage thus flows through the multiple threads 62 under pressure reducing conditions and a helical type of a flow pattern is concurrently established in the beverage whereby when the plurality of ports or apertures 54 in the slide valve means are brought into horizontal alignment with an annular space within the spacer sleeve 63 but below the lower end of the center block 43, beverage being released from the threads 62 will then flow in a continuing helical or centrifugally directed path through the bores or ports 54 into and axially downwardly of the enlarged lower end 51 of the tubular valve means 50. A vertical, relatively short discharge path of uniform dimensions is provided in the lower end sleeve 40 for the beverage when the tubular valve means 50 is moved to its lowest position.

The position of the tubular valve means 50 and whether or not it is in its open or closed position is controlled by a suitable member, such as a piston 64, that is suitably attached to the valve means 50 adjacent its upper end. This piston 64 is slidably received in a chamber 65 formed in the upper end block 44 and a coil spring 66 normally is compressed between the pis-

ton 64 and the upper end of the center block 43 to urge such piston and thus the tubular valve means 50 normally to its upper position, FIG. 1, where the valve is closed. Pressure for operating the valve means 50 is supplied through a conventional inlet fitting 67 attached to the upper end block 44 and communicating with the chamber 65 by a bore 68 drilled or otherwise provided in the upper end block whereby when pressure is supplied to the fitting 67, the piston 64 can be driven downwardly rapidly and the filling head 10 is adapted to discharge beverage therefrom.

A probe 70 is also provided in the filling head 10 and it extends axially of the filling head for certain novel control functions and/or movements, to be hereinafter described in more detail. In order to position the probe and provide for independent movement thereof, an extension sleeve 71 is secured to the upper end of the upper end block 44, as by a lock nut 72 engaging a shoulder 73 provided on the sleeve 71, and in threaded engagement with the upper end of the end block 44. Such extension sleeve 71 has its bore in communication with the center bore of the filling head that connects to a container or bottle B engaged by the filling head. The counterpressure gas can be supplied to a fitting 74 suitably attached to the extension sleeve 71 and to which the conduit 36 connects for passage of the counterpressure gas to or from such extension sleeve as hereinafter described. A probe positioning cylinder 75, usually electrically conductive, is attached to the upper end of the extension sleeve 71 by a lock nut or collar 76 engaging a shoulder 77 provided on the periphery of the cylinder 75 adjacent its lower end and which lock nut 76 in turn engages a threaded upper end portion of the extension sleeve 71. The drawing shows that the probe 70 extends up into the cylinder 75 and the probe is sealed in relation to the cylinder as by means of an O-ring 78 operably carried by a conductive plug 79 secured against the upper end of the end block 44 by the lower end of the cylinder 75. The plug 79 is likewise sealed on its peripheral portion in relation to the extension sleeve 71 by an O-ring 80. An elongate piston 81 is slidably received in the cylinder 75 and it has a counterbored section or bore 82 provided in the lower end thereof and with a spring 83 being compressed between the upper end of the counterbore 82 and the plug 79 whereby the piston 81 is normally moved to its uppermost or elevated position. The upper end of the probe 70 is operatively secured to the piston 81 at an upper portion thereof, as by the spring 83 forcing a washer 84 carried by the probe up against the end of the counterbore 82.

In order to control the vertical extended position for the probe 70, a control sleeve 90 is shown in threaded engagement with the upper end of the cylinder 75. The piston 81 has an integral axially extending rod 91 projecting vertically upwardly from its upper end and extending through an aperture in the upper end of the control sleeve 90. A stop or limitation member, such as a washer or split ring 92, is secured to the outer end of the rod 91 whereby downward movement of the probe is controlled by the washer 92 bearing on the upper end of the control sleeve 90. By adjustment of the position of the control sleeve 90, the extent of downward movement of the probe is thereby controlled. Pressure for operating the piston 81 in the cylinder 75 is preferably obtained in a unitary manner with pressure for operating the tubular valve means in the filling head and thus

a fitting 93 is shown engaging the cylinder 75. The fitting 93 is connected to the fitting 67 by a tube 94 and with an inlet 95 being provided in the cylinder 75 and connecting to the fitting 93 which in turn is adapted to receive suitable pressure fluid from a conventional supply source thereof through a supply line 96. Hence, when operating conditions are established, operating pressure will be supplied for moving the probe 70 a relatively long distance such as about 2 to 3 inches in the filling head 10 while the tubular valve sleeve is moved only a short distance, such as one-half inch or so, to open the filling head for beverage flow purposes. Thus, the probe 70 can be extended several inches downwardly with relation to the lower part of the filling head and extend into a bottle a desired distance. The probe 70 normally is electrically conductive and has electrical circuit and control means 100 connected thereto by a lead 101. Hence, when a circuit is completed through the probe by it contacting beverage received within the container or bottle B, a control signal can be sent from the control means 100 to suitable apparatus, such as a solenoid valve 102, to terminate beverage input action by removing the operating pressures on the pistons 64 and 81. The probe 70 is also then retracted. The frame 22 is grounded and the beverage flowing through the valve 50 and to the bottle and collecting therein completes the circuit to the probe. The switch 31 connects to the control means 100 by leads 103 and 104 so that such control means can not be operative to open the solenoid valve 102 for beverage flow until the desired counterpressure is set up in a bottle through the conduit 35 when the valve 38 is open.

While most of the components of the invention can be made from any suitable material, the components adjacent or contacting the probe 70 should be electrically non-conductive. Hence, it has been found that it is very desirable to make such members, such as the valve means 50, from a glass fiber impregnated resin composition of conventional construction. Preferably a low friction, rigid plastic material is used which can be machined and shaped to desired contours. The sleeve 71 and tube 94 are also insulators to separate the probe electrically from the frame 22.

Pressure to regulate action of the control switch 31, which is of the differential pressure type, is supplied to the upper side of the diaphragm 34 by a bore 120 formed in a member 121 secured to the upper portion of the frame 21.

A suitable conduit 122 connects the bore 120 to a controllable source (not shown) of gas pressure.

A lower guide sleeve 97 made from a suitable insulating material is secured to the valve means 50 to protrude downwardly therefrom and define the inner portion of the flow path for beverage from the filling head. A guide collar 98 on the sleeve 97 slidably engages a lower portion of the probe. Any other means as desired may be used to complete the beverage flow discharge path. Likewise, the control means 100 can connect to the probe 70 in any suitable manner.

The fixed frame 21 is designed to receive a pin or bolt 130 between spaced bosses on the frame to secure the filling head to the filling machine. A resilient pad 131 is positioned on a part of the fixed frame to limit downward movement of the movable frame 22.

By use of the apparatus shown, it is possible to move the entire filling head 10 a short distance, such as about an inch, in bringing it to and from operative engage-

ment with a bottle, and the probe in the filling head can be given an independent, adjustable movement to extend into a bottle a desired distance. The probe 70 is separately retracted from a filled bottle after the bottle is filled whereby the probe will not interfere with bottle engaging and disengaging action as such motion takes place when the probe is in the retracted position shown in FIG. 1. In the apparatus as shown, the probe is retracted simultaneously with termination of the beverage input.

From the foregoing, it is noted that the objects of the invention have been achieved and that a novel improved filling head is provided.

While one complete embodiment of the invention has been disclosed herein, it will be appreciated that modification of this particular embodiment of the invention may be resorted to without departing from the scope of the invention as defined in the appended claims.

What is claimed is:

1. A filling head for apparatus for filling articles with beverage and comprising
 a frame for engaging the top of an article and having a vertically positioned tubular section therein,
 means engaging said frame to move it vertically to 25 and from engagement with the top of an article positioned for filling,
 a valve seat means in said tubular section,
 a tubular valve means having a bore slidably positioned in said tubular section for flow of beverage 30 through said valve seat means when said valve means is moved to an open position,
 means for supplying beverage to said tubular valve means and said valve seat means,
 first piston and cylinder means operatively engaging 35 said valve means to move it vertically and control the opening and closing thereof,
 an elongate probe slidably positioned in said valve means and extending from both ends thereof, said probe having a portion extending downwardly from 40 said valve means into an article to contact beverage therein when at a predetermined level, electric circuit control means for said valve means engaging means connected to said probe to be actuated when beverage contacts its lower end,
 a second piston and cylinder means on said frame and operatively engaging the upper end of said probe to control the vertical relationship thereof to 45 said frame and movement of said probe as well as the length of such movement, said probe being adapted to be extended below said frame, and

common pressure supply means operatively connecting to both of said piston and cylinder means for simultaneous actuation thereof but independent movement of said probe.

2. A filling head for apparatus for filling articles with beverage and comprising

a frame for engaging the top of an article and having a vertically positioned tubular section therein, said frame being engageable with the top of an article positioned for filling,
 a valve seat means in said tubular section,
 a tubular valve means having a bore slidably positioned in said tubular section for flow of beverage through said valve seat means when said valve means is moved to an open position,
 means for supplying beverage to said tubular valve means and said valve seat means,
 first piston and cylinder means positioned in alignment with and operatively engaging said valve means to move it vertically and control the opening and closing thereof,
 an elongate probe slidably positioned in said valve means and extending from both ends thereof, said probe having a portion extending downwardly from said valve means into an article to contact beverage therein when at a predetermined level, electric circuit control means for said valve means engaging means connected to said probe to be actuated when beverage contacts its lower end,
 a second piston and cylinder means on said frame, and positioned in alignment with and operatively engaging the upper end of said probe to control the vertical relationship thereof to said frame and movement of said probe as well as the length of such movement, said probe being adapted to be extended below said frame, and
 common pressure supply means operatively connecting to both of said piston and cylinder means for simultaneous power actuation thereof to open said valve means and to move said probe longitudinally downwardly.

3. A filling head as in claim 2 and including means for controlling the length of movement of said probe, said pressure supply being a fluid and means to terminate supply of the pressure to said piston and cylinder means for simultaneous movement of said probe upwardly and closure of said valve means, both of said piston and cylinder means having springs therein to move them to non-actuated positions.
